Primary Examiner—Ted Shooman*Assistant Examiner*—Mitchell I. Siegel*Attorney, Agent, or Firm*—Fay, Sharpe, Beall, Fagan, Minnich & McKee[57] **CLAIM**

The ornamental design for a ball striking face plate of a golf wood, as shown and described.

DESCRIPTION

FIG. 1 is a perspective view of the present design; and, FIG. 2 is a front view of the present design.

That portion of the figures depicted in broken lines does not form a portion of the claimed invention.

The stipple pattern on the drawing figures is representative of the color black.
